DESIGN FOR A COMBINED WATCHCASE AND WATCH BRACELET OR SIMILAR ARTICLE

Mathias Austin, Flushing, N. Y., assignor of fifty per cent to Marcus Reller, New York, N. Y.

Application December 2, 1948, Serial No. 149,917

Term of patent 7 years

(Cl. D45—4)

To all whom it may concern:

Be it known that I, Mathias Austin, a citizen of the United States, residing at Flushing, in the county of Queens and State of New York, have invented a new, original, and ornamental Design for a Combined Watch Case and Watch Bracelet or Similar Article, of which the following is a specification, reference being had to the accompanying drawing, forming part thereof.

In the drawing,

Fig. 1 is a perspective view of a combined watch case and watch bracelet or similar article, showing my new design;

Fig. 2 is a bottom plan view thereof; and
Fig. 3 is a side elevational view thereof.

I claim:

The ornamental design for a combined watch case and watch bracelet or similar article, as shown.

MATHIAS AUSTIN.
